UNITED STATES PATENT OFFICE.

GEORGE WHITE, OF JERSEY CITY, NEW JERSEY, ASSIGNOR TO PANAYIOTIS PANΟULIAS, OF JERSEY CITY, NEW JERSEY.

TRANSFER MECHANISM.

1,378,503.

Specification of Letters Patent. Patented May 17, 1921.

Original application filed July 19, 1913, Serial No. 779,985. Divided and this application filed May 15, 1918. Serial No. 234,642.

To all whom it may concern:

Be it known that I, GEORGE WHITE, a citizen of the United States, and a resident of Jersey City, in the county of Hudson and State of New Jersey, have invented certain new and useful Improvements in Transfer Mechanism, of which the following is a specification.

My invention relates to mechanism for transferring articles, particularly from a support to a conveyer, and has been designed primarily for the purpose of taking rows of confections or candies, or any other articles which it may be desired to provide with a coating or ornamentation, from a support or receiving conveyer to a delivery conveyer which carries these articles to the machine employed for applying such coating or ornamentation.

20 A specific example of my invention will now be described with reference to the accompanying drawings, and the novel features will then be pointed out in the appended claims.

25 In the said drawings, Figure 1 is a side elevation of the machine, with parts in section and parts omitted; Fig. 2 is a detail horizontal section on line 2—2 of Fig. 1; Fig. 3 is a transverse section taken substantially on line 3—3 of Fig. 1; Fig. 4 shows on an enlarged scale, and in substantially the same position as in Fig. 1, the parts appearing at the left-hand portion of Fig. 1; Fig. 5 also shows the parts at the left-hand portion of Fig. 1, but in a different position; Fig. 6 shows substantially the same parts as Fig. 5, but in a still different position; and Fig. 7 is a partial plan view of the left-hand end of my machine.

40 The candies or other articles to be coated (hereinafter referred to under the generic term of "cores") are placed in a box 30 having an inclined bottom 31. Immediately adjacent to the front edge of the inclined bottom 31 is an inclined feed board 32, preferably of a steeper inclination than the bottom 31. Over this feed board the articles from the box 30 are fed downwardly by means of brush mechanism 33 of the character more fully described and claimed in my Letters Patent of the United States No. 1,266,734, issued May 21, 1918, on my application Serial No. 779,985, filed July 19,

1913, of which my present application is a division. [55]

Adjacent to the said box and brush mechanism is a transverse shaft 34 carrying a ratchet 34' for operating a mechanism to agitate the bottom 31 as set forth in my above-mentioned patent. This shaft 34 also carries sprocket wheels 35 supporting chains 36, one at each side of the machine, said chains being endless and also passing, at the other end of the machine, around similar sprocket wheels 37. [65]

An intermittent motion, always in the same direction, is imparted to the chains 36 by the following mechanism: Each of said chains is engaged by a toothed wheel or roller 38, journaled at 39 upon a lever 40, 70 the two levers 40 being secured to a rock shaft 41, journaled in a stationary bracket 42. A weight 43, secured to an arm 44 carried by the shaft 41, tends to bring the levers 40 to the position shown in Figs. 1 75 and 4. To the shaft 41 is also secured an arm 45, to which is pivoted at 46 a rod 47, the other end of which carries a roller 48 engaged and operated by a cam 49 secured to the main shaft 50. This shaft is driven 80 in any suitable manner, as by a belt or chain 51 running to a pulley or sprocket 52 on a power shaft. The rod 47 is supported in such a way as to slide lengthwise therein, in a guide sleeve 53 rigid with an arm 54 which is mounted loosely on the shaft 50. Each of the levers 40 carries a pawl 55 engaging the respective roller 38 and holding such roller against rotation when the lever moves toward the right from the position shown in Figs. 90 1 and 4, but allowing said roller to turn idly when the lever returns toward the left, under the influence of the weight 43. Thus, as the cam 49 causes the levers 40 to swing toward the right, the chains 36 will be caused to travel, their upper runs moving toward the left in Figs. 1 and 4. During the return movement of the levers 40, under the influence of the weight 43, the rollers 38 rotate idly as stated above, and the chains 36 therefore remain stationary. [95]

Each of the chains 36 is connected at suitable intervals with cross bars 57 arranged to travel over a table 58 on which the cores drop from the inclined feed board 32. The 105 lower end of the feed board is at a sufficient

distance from said table 58 to allow the cross bars 57 and their projections, referred to hereinafter, to pass freely. The forward edge of each cross bar 57 is notched or 5 toothed, as shown in Fig. 7. The cross bars 57 therefore will not only feed the cores toward the left on the table 58, but will also re-arrange or re-align such cores perfectly. The cross bars 57 also serve as means for 10 operating the brush mechanism in the manner set forth in my above-mentioned patent. The distance between two successive cross bars 57 is preferably approximately equal to the extent of the movement or throw given 15 to the chains 36 at each operation of the levers 40.

In some cases, possibly, a greater number 20 of cores will reach the table 58 than required to fill all the notches of the cross bars 57. Such extra or surplusage cores would naturally stay in front of the row of cores held 25 in the notches of the bar 57. In order to eject such surplusage cores, a trap door 75, pivoted at 76 and pressed upward by a 30 spring 77, may be located in the table 58, at a suitable distance in advance of the feed board 32. This trap door is made with upwardly-extending lugs 78 provided with laterally-extending pins 79 located in the path 35 of projections 80 connected with the bars 57 and preceding them. At the proper time the projections or pins 80 will engage the pins 79 and thus open the trap door 75 to discharge any cores which are in advance 40 of the row 74. Immediately thereafter, as the pins 80 clear the pins 79, the door 75 will fly upward and close the opening in the table 58, so that said door will virtually form a part of the table, allowing the row 45 of cores 74 to proceed over the closed door 75 to the forward portion of the table 58. It is to be understood, however, that this trap door arrangement is not essential to my invention, that is to say, a continuous table 58 may be employed if preferred.

The cores being advanced intermittently 50 in rows, as described, will finally be pushed onto a belt or other endless conveyer 81 the upper run of which is at the same level with the table 58 and immediately in advance thereof. This conveyer is given a continuous motion, in the same direction as the chains 36, in any suitable manner, as by 55 means of a chain 82 running over a sprocket 83 secured to the main shaft 50 and also over a sprocket 84 secured to one of the shafts 85 carrying the rollers 86 on which the conveyer 81 is supported. One of these shafts 85 is preferably co-axial with the 60 shaft carrying the sprocket wheels 37, or, as shown, the sprockets 37 are mounted on the forward shaft 85, it being understood, of course, that the sprockets 37 turn independently of the corresponding roller 86, which 65 may be accomplished by securing said roller

rigidly to its shaft, while mounting the sprocket wheels 37 loosely on the same shaft. The cross bars 57 push the cores from the table 58 onto the conveyer 81, and as soon as the cross bar 57 stops, the conveyer 81, 70 which continues to move (preferably at a greater linear speed than the chains 36), will draw the row of cores out of the notches of the cross bar 57, feeding them forward so as to separate the cores from said cross bar 75 and to form a space between the cross bar and the row of cores. Into this space is adapted to descend a pin-bar or rake 87 having pins 88 projecting downwardly and disposed in V-shaped fashion (see Fig. 7), corresponding in arrangement to the V-shaped notches of the cross bars 57. Thus, if the cores should become disarranged during the short interval between their engagement with the cross bar 57 and their subsequent 85 engagement with the rake 87, the latter owing to the V-shaped arrangement of its teeth 88, will re-align said cores to their proper position.

The rake 87 is intended to transfer the 90 row of cores from the conveyer 81 to another conveyer 89, for taking the cores to another machine, say a chocolate-coating machine, for further treatment. The cores, however, do not pass directly from the conveyer 81 to 95 the conveyer 89, but on their way from one conveyer to the other the cores pass over a movable or tilting table 90, mounted to swing about a horizontal transverse axis 91. In one position, Fig. 5, the rear end of the 100 table 90 is raised away from conveyer 81, so as to allow the cross bars 57 with their projections to pass under said table. In the other position, Figs. 1, 4 and 6, the table 90 is swung down to bring its rear end into 105 registry with the conveyer 81, while in the position first mentioned the table 90 is in registry with, or in operative relation to, the conveyer 89. The tilting movement of the table 90 is obtained by the following 110 mechanism: On the main shaft 50 is secured a cam 92 adapted to engage a roller 93 carried by a rocking member 94 fulcrumed on a rock shaft 95 journaled in brackets 96, that is to say, the member 94 is loose on the 115 shaft 95. A link 97 is pivotally connected at 98 with the rocking member 94 and at 99 with the table 90, in the rear of its pivot or fulcrum 91.

The rake 87 is secured to a carriage 100 120 provided with rollers 101 adapted to run in U-shaped guides 102 secured to the tilting table 90 at each side thereof. The axle of one of the rollers 101 is extended as shown in Figs. 3 and 7, and pivotally connected 125 with a link 103, the other end of which is pivotally connected with an arm 104 secured to a rock shaft 105. It will be understood that this arrangement is provided on each side of the machine. The shaft 105 has an 130

arm 106 pivotally connected at its outer end with a link 107, the upper end of which has a pivotal connection with a crank arm 108 secured to the main shaft 50.

- 5 The guides 102 stop short of the rear end of the table 90, and inasmuch as the rake 87 is to travel beyond the rear end of said table, additional guides are provided for the carriage 100 at the rear portion of its travel.
- 10 These additional guides 109 are similar to the guides 102 and are adapted to register therewith (Figs. 1 and 4), but at other times (Fig. 6), the guides 109 are raised as explained in detail hereinafter, to lift the rake 15 87 out of the path of the bars 57 and of the cores A. For this purpose, the supplementary guides 109 are each provided with a downwardly-extending bar 110 having a slot or recess 110' into which extends a pin 20 111 projected from the end of the crank arm 112 secured to the rock shaft 95. A cam 120 on the shaft 50 engages a roller 121 on a crank arm 122 secured to the shaft 95, to rock the latter (see Figs. 3 and 6). The bars 110 move vertically in guides 113. I may provide a vertically-adjustable stop 114 to arrest the table 90 at the proper point when swung into registry with the conveyer 81.
- 25 30 As shown in the drawings, the table 58 and the conveyer 81 registering therewith are horizontal. In some cases, it may be desirable to cause the said table to be inclined slightly upward toward the delivery end, so as to cause the cores to remain in better contact with the feed bars 57. For this purpose, the entire portion 116 of the machine to the rear of the forward shaft 85 may be mounted to swing on said shaft, 35 the rear end of said frame portion being supported adjustably on rods 117. For instance, said rods may extend loosely through the heads of bolts 118 passing horizontally through said frame portion, the 40 parts being locked after adjustment, by means of nuts 119.

The operation will be readily understood and may be briefly described as follows:

- The articles or cores passing from box 30 50 are fed over the feed board 32 by the brush mechanism 33 as described in my above-mentioned patent, and thus reach the table 58 over which they are fed intermittently by the notched bars 57. When they reach 55 the left-hand end of the table 58, the bar 57 engaging them will push them over onto the constantly-moving conveyer 81, the bar coming to a stop in about the position illustrated by Fig. 5. Then the table 90 tilts 60 to the position shown in Figs. 1, 4, and 6, the rake 87 however, being still supported by said table 90, that is to say, the rollers 101 are still in the guide portion 102. The rake 87 is then traveling rearward along 65 the table 90 which is now in registry with
- the guide portion 109, as in Figs. 1 and 4. After the rollers 101 of the rake carriage have passed from the guide 102 to the guide 109, and before the rake in its rearward movement can collide with the cores now 70 being fed forward by the continuously-moving conveyer 81 away from the now stationary bar 57, the guide 109 rises to the position shown in Fig. 6 so that the rake can pass over the cores A. Fig. 6 shows the 75 rake almost, but not quite, in its rear position, that is to say, the rake will travel a little farther to the right while the cores continue to travel toward the left. The guide 109 then drops, carrying the rake 87 80 to the position shown in Figs. 1 and 4, so that the rake will be in the rear of the line of cores. Then the rake travels forward again, pushing the cores in front of it over the tilting table 90, and after the rollers 85 100 105 110 115 120 125 130 135 140 145 150 155 160 165 170 175 180 185 190 adapted to receive articles discharged from said outlet, chains having portions extending lengthwise of said table adjacent thereto, and cross bars connecting said chains and arranged to move lengthwise over said table and under the outlet of said box, said bars being arranged to move between the chains and the table.

2. The combination of a table adapted to support articles, chains having portions extending lengthwise of said table adjacent thereto, and cross bars connecting said chains and arranged to move lengthwise over the table and feed the articles thereon, said bars being arranged to move between the chains and the table.

3. The combination of a table adapted to support articles, means, movable adjacent to said table, for feeding said articles lengthwise of the table, a trap door in said table, closing in a direction toward said feeding means, and means for opening said trap door in the direction away from said feeding means.

4. The combination of a box having an outlet, a table arranged to receive articles from said outlet, cross bars movable over the table to feed said articles lengthwise thereof, a trap door in the table, for discharging surplus articles, and means, connected with the cross bars, for opening said trap door.

5. The combination of a table adapted to support articles, means for feeding said articles lengthwise of the table, a trap door in the table, for discharging surplus articles, and means, connected with said feeding means, for opening said trap door.

6. The combination of a table adapted to support articles, means for feeding said articles lengthwise of the table, a trap door in the table, a spring for normally pressing said door to the closed position, and means, connected with said feeding means, for opening said trap door against the tension of its spring.

7. The combination of a table adapted to support articles, means, movable adjacent to said table, for feeding said articles lengthwise of the table, a trap door movable to a position in which it alines with said table, and also movable to an open position, in a direction away from said feeding means, a spring pressing said trap door toward said feeding means to said closed or alining position, and means for moving said trap door to its open position against the action of its spring, in a direction away from said feeding means.

8. The combination of a table, means for feeding articles thereto, a cross bar extending over the table and adapted to feed articles lengthwise thereof, a trap door in the table, for discharging surplus articles, and

means, connected with said cross bar, for actuating the trap door.

9. The combination of a table, means for feeding articles thereto, a cross bar extending over the table and adapted to feed the articles lengthwise thereof, said bar having a series of notches to receive and hold a row of articles, a trap door in said table, and means, connected with said bar and projecting in advance thereof, for opening the trap door and allowing it to close again before the row of articles held in the notches of the bar reaches the trap door.

10. The combination of a conveyer adapted to support articles, cross bars movable lengthwise over said conveyer, means for imparting an intermittent motion to said bars, means for causing the conveyer to move while the said bars are stationary, and thereby carry articles away from said cross bars, and means movable transversely of the conveyer, to enter the space between a cross bar and the articles which have been carried away therefrom by the action of said conveyer, said means being also movable lengthwise of the conveyer to take said articles therefrom.

11. The combination of a conveyer adapted to support articles, cross bars movable lengthwise of said conveyer, means for giving the conveyer a forward motion relatively to said cross bars and thereby carry articles in engagement with the front of a cross bar, away from such cross bar, and means movable transversely of the conveyer, to enter the space between a cross bar and the articles which have been separated therefrom by the action of said conveyer, said means being also movable lengthwise of the conveyer to take said articles therefrom.

12. The combination of a table, a conveyer registering with the delivery end of said table, cross bars movable lengthwise over said table and over said conveyer, means for imparting an intermittent motion to said bars, means for imparting a continuous motion to the conveyer so that it will carry articles resting against said cross bars, away from the cross bars, and means movable transversely of the conveyer, to enter the space between a cross bar and the row of articles which has been separated therefrom by the action of said conveyer, said means being movable lengthwise of the conveyer to take said row of articles therefrom.

13. The combination of a table, a conveyer registering with the delivery end of said table, cross bars movable lengthwise over said table and over said conveyer, and a rake movable toward and from the conveyer and also movable lengthwise thereof to carry the articles fed by said cross bars, away from the conveyer.

14. The combination of a table, a conveyer registering with the delivery end of said table, cross bars movable lengthwise over the table and the conveyer and having notches forming seats for articles to be fed over the table, and a rake having pins set in V-fashion corresponding to the notches of said cross bars, said rake being movable lengthwise of and beyond the said conveyer, to carry the articles away therefrom.

15. The combination of a support over which articles are adapted to travel, a cross bar movable lengthwise over said support and having notches forming seats for articles to be fed over said support, and a rake having pins set in V-fashion corresponding to the notches of said cross bar, said rake being movable lengthwise of said support.

16. The combination of a support over which articles are adapted to travel, and a feed member movable lengthwise of said support to feed the articles thereon, and also movable away from the support so that such member may be carried above and past such articles, and toward the support to bring such member again to a feeding position.

17. The combination of a table, an endless conveyer one run of which registers with the delivery end of the table, rollers supporting said conveyer, a frame mounted to swing about an axis coinciding with that of one of said rollers, means for securing said frame after adjustment, the table and conveyer being carried by said frame, chains movable adjacent to said table and to said conveyer, cross bars connecting said chains and movable over the table and the conveyer, and sprocket wheels carrying said chains, one set of such sprocket wheels being co-axial with the pivot of said frame.

18. The combination of a table, an endless conveyer one run of which registers with the delivery end of said table, a frame carrying said table and conveyer and mounted to swing for adjustment about an axis adjacent to the delivery end of the conveyer, means for securing said frame after adjustment, chains movable lengthwise adjacent to said table and to said conveyer, cross bars connecting said chains and movable over the table and over the conveyer, and sprocket wheels carrying said chains, one set of such sprocket wheels being co-axial with the pivot of said frame.

19. The combination of a conveyer, an-

other conveyer at a distance therefrom, a tilting table adapted to register with one or the other of said conveyers, means for carrying articles from one conveyer to the other over the tilting table, and means for actuating said table.

20. The combination of two conveyers arranged to feed articles in substantially the same direction, a tilting table ranging lengthwise of said conveyers and having its respective ends adapted for registry with said conveyers, means for actuating the table, and means for carrying articles from one conveyer to the other over said table.

21. The combination of two conveyers arranged to feed articles in substantially the same direction, a table ranging lengthwise of said conveyers and interposed between them, said table being mounted to swing about an axis transverse relatively to the conveyers, means for actuating said table, and means for carrying articles from one conveyer to the other over the table.

22. The combination of two supports, a tilting table interposed between them, means for actuating said table to register first with one support and then with the other, and means for carrying articles from one support to the other over said table.

23. The combination of two supports, a tilting table between them, cross bars movable lengthwise of one of said supports, to feed the articles thereon toward the said table, a carriage movable lengthwise of the table and beyond the end thereof, a feed member connected with said carriage, to carry the articles from one support to the other, a movable guide for said carriage, at the point where the latter travels beyond the table, and means for moving said guide away from the support to allow the feed member to pass over said articles.

24. The combination of two supports, a tilting table between them having its fulcrum at its central portion arranged transversely of said supports, a cross bar movable lengthwise of one of said supports and adapted to pass between said support and said table when the latter is tilted out of registry with said support, and means for carrying articles from one support to the other over said table.

In testimony whereof I have signed this specification.

GEORGE WHITE.
